(57) **CLAIM**

The ornamental design for a ring and hook game, as shown and described.

DESCRIPTION

FIG. 1 is a front, left perspective view of a first embodiment of a ring and hook game depicting my new design;
FIG. 2 is a left side view of the ring and hook game depicted in FIG. 1;

FIG. 3 is a right side view of the ring and hook game depicted in FIG. 1;

FIG. 4 is a front view of the ring and hook game depicted in FIG. 1;

FIG. 5 is a rear view of the ring and hook game depicted in FIG. 1;

FIG. 6 is a top view of the ring and hook game depicted in FIG. 1;

FIG. 7 is a bottom view of the ring and hook game depicted in FIG. 1; and

FIG. 8 is a perspective view of the ring and hook game depicted in FIG. 1 shown installed for use in a trailer hitch;
FIG. 9 is a front, left perspective view of a second embodiment of a ring and hook game depicting my new design;

FIG. 10 is a left side view of the ring and hook game depicted in FIG. 9;

FIG. 11 is a right side view of the ring and hook game depicted in FIG. 9;

FIG. 12 is a front view of the ring and hook game depicted in FIG. 9;

FIG. 13 is a rear view of the ring and hook game depicted in FIG. 9;

FIG. 14 is a top view of the ring and hook game depicted in FIG. 9;

FIG. 15 is a bottom view of the ring and hook game depicted in FIG. 9;

FIG. 16 is a perspective view of the ring and hook game depicted in FIG. 9 shown installed for use in a trailer hitch; and,

FIG. 17 shows the ring and hook game in its environment of use with the arrow showing the direction of movement.

The broken lines tubular lock, in FIGS. 9-17, depict portion of the ring and hook game that forms no part of the claimed design. The broken lines showing of a truck with mounting hitch, illustrate environmental structure and form no part of the claimed design. The arrow and the broken line tittered hooks in FIG. 17, show the direction of the movement and form no part of the claimed design. The ring and hook game is shown with a symbolic break in its base. The appearance of any portion of the article between the break lines forms no part of the claimed design.

1 Claim, 13 Drawing Sheets
